Primary Examiner — Jeffrey D Asch*(74) Attorney, Agent, or Firm* — Banner & Witcoff, Ltd.(57) **CLAIM**

The ornamental design for a handset, as shown and described.

DESCRIPTION

FIG. 1 is a perspective view of a handset showing our new design; and,

FIG. 2 is a front view thereof.

The broken lines of the handset in the figures and the unshaded regions therein are for illustrative purposes only and form no part of the claimed design. The contrast in shading represents a contrast in appearance only and does not represent any particular color, material, texture or finish.
